UNITED STATES PATENT OFFICE

LOUIS BEON, OF SALEM, NEW JERSEY, ASSIGNOR TO SALEM GLASS WORKS, OF SALEM, NEW JERSEY, A CORPORATION OF NEW JERSEY

LEER

Application filed December 10, 1931. Serial No. 580,080.

The present invention relates to leers, particularly for annealing ware of variable heights.

In annealing tall bottles, for example, it is important that the annealing heat be controlled to insure adequate annealing of the lower portions of the bottles without subjecting the upper portions to too much heat, which may be sufficient to cause deformation of the bottle necks where the heat around the upper portion of the bottle is sufficient to soften the glass.

In some instances efforts have been made to avoid undesirable neck softening by reducing the temperature in the upper portion of the leer. This reduction has generally been accompanied by a corresponding reduction of the heat in the lower portion of the leer, as a result of which the lower portions of the ware, particularly in the case of relatively tall bottles, have been insufficiently annealed.

Where the height of the leer, inside, is sufficient to accommodate relatively tall bottles, a considerable amount of heat is wasted in the annealing of small bottles of a few inches height.

Constructions have been proposed for regulating or controlling the annealing heat to which the upper and lower portions of relatively tall bottles, for example, are to be subjected. Some of these constructions involve a relatively movable baffle plate located within the leer between the ceiling and floor thereof, such plates being raised or lowered to accommodate ware of different heights. Such baffle plates, however, are subject to the disadvantage that heat is transferred to and through such plates and the heated air rises past them into the upper portion of the leer.

It has also been proposed to raise and lower the ceiling of the leer with respect to the floor thereof, or with respect to an endless belt carrying the ware through the leer, but these constructions are likewise disadvantageous in some respects, such as that, in adjusting the ceiling of the leer vertically, the thickness of insulation of the leer walls has been varied, thus not only resulting in

a loss of heat but introducing a variable factor in the control of the proper annealing temperatures. Another objection to such constructions has been that, in accomplishing variability in height of the leer for ware of different heights, a considerable heat loss has resulted due to leakage where the parts are relatively movable.

Accordingly, it is an object of the present invention to provide a leer having parts which are movable to accomplish efficient annealing of ware of different heights, whereby adequate annealing of both the upper and lower portions of ware, such as tall bottles, may be accomplished without danger of undue softening of the bottle necks or upper portions of the ware.

Another object is to provide a leer comprising relatively movable upper and lower sections in which these sections may be movable relatively without the occurrence of any variation in the wall thickness or insulation.

A further object of the invention is to provide, in connection with this relative movement, means for insuring tightness of the relatively movable parts after their adjustment, said means permitting relatively free movement of the leer sections when desired and providing a seal after the adjustment, resulting in a wall tightness comparable to that of known leers having relatively fixed or unchangeable interior height.

Further objects and advantages of the invention will appear from the following description, taken in connection with the accompanying drawings which illustrate, by way of example, a preferred embodiment of the invention, and in which—

Figure 1 is a top plan view illustrating the ends and an intermediate portion of a leer constructed in accordance with the present invention;

Figure 2 is a side elevation of the leer of Fig. 1, with the driving means for the ware-carrying belt omitted;

Figure 3 is a transverse sectional elevation on an enlarged scale and taken on the line 3—3 of Fig. 2;

Figure 4 is a fragmentary vertical sec-

100

tional view of two relatively movable parts of the leer and on a somewhat enlarged scale;

Figure 5 is a fragmentary top plan view 5 showing a preferred form of locking or sealing means;

Figure 6 is an enlarged fragmentary perspective view of one of the rails supporting the conveyor belt which carries the ware 10 through the leer; and

Figure 7 is a fragmentary vertical section view, taken on the line 7—7 of Fig. 3, and on the same scale as Fig. 4.

Referring in detail to the drawings, the 15 leer here shown as embodying a preferred form of the invention is provided with a stationary bottom consisting of layers 11 and 12 of insulating material resting on a bottom plate 13 which, in turn, is supported 20 by suitable framework 15. The bottom 13 is preferably provided with side flanges 16 between which is received the lower insulating layer 12. The flanged plates 18 receive 25 between them the insulating layer 11, holding it in fixed relation to the lower insulating layer 12. Supported upon each flanged plate 18 is a side plate 20 extending the length of the leer, each plate 20 supporting a ware guide 22, for guiding ware carried 30 longitudinally through the leer upon an endless wire belt conveyor 24, idle rollers 25 being provided outside of and below the bottom of the leer for the lower run of the conveyor. The upper run of the conveyor 35 is supported by a plurality of spaced rails 26 extending substantially lengthwise of the leer and supported in fixed position therein upon a plurality of firebricks 28, or other suitable supports. Above the bottom of the 40 leer and below the rails 26 are located a plurality of heating elements 30, which are preferably composed of electrical resistance to facilitate their convenient control in groups. The heat supplied by these elements passes upwardly in the leer through 45 the interstices of the wire belt conveyor for annealing the ware carried thereby.

The stationary rails 26, upon which rides the upper run of the conveyor, instead of 50 extending exactly parallel with the length of the leer, preferably extend at a slight angle thereto in order to distribute wear on the lower face of the upper run of the belt. For example, the rails 26, at the ware entrance end of the leer, may extend toward 55 the right side of the leer and the rails at the ware exit end of the leer may extend inwardly of the leer toward the same side. This construction not only distributes the wear on the conveyor belt but also prevents the conveyor from being biased toward either side as it travels through the leer.

In order further to reduce the wear upon the conveyor belt, each rail 26 is preferably 60 provided in its upper face with a plurality

of holes or depressions, preferably with flat bottoms, for the insertion of lubricating plugs, for example, of compressed graphite or other lubricating material capable of withstanding relatively high temperatures, such, for example, as 1800° F.

The conveyor belt is moved through the leer by any suitable mechanism, which, for example, may include end rollers and suitable driving means such as a motor 36 through reduction gearing 38.

The invention includes an upper leer section, vertically movable with respect to the leer bottom, and this upper movable section 80 preferably includes a top 40 and side walls 42, all carried within the sheet metal cover 44.

As indicated in Figure 2, the top of the leer is preferably provided with its thickest and most effective insulation at the ware entrance end, herein shown as being at the left hand end as viewed in Figure 2, the thickness of this insulation being reduced in steps toward the ware exit end of the leer.

The side walls 42 of the movable section 85 may be provided with insulation of unvarying thickness throughout their length, or of varying thickness or effectiveness, if desired.

The invention includes means for supporting and for raising and lowering the upper movable section and, as embodied in the present illustrated form of the invention, an inverted channel iron 48 extends lengthwise 90 of the leer along the bottom of each side wall 42, being secured thereto by vertically extending through-bolts 50 whose upper ends extend beyond the leer top and are suitably secured to carrying beams 52, one of which 100 extends lengthwise of the leer horizontally above each side wall thereof. The beams 52, at suitable intervals therealong, carry fixed thereto pulleys 54.

Cooperating with the pulleys on each side 105 are cables 56, each having one end fixed, as at 58, in the upper transverse supports 60 carried by the vertical members 62 of a framework within which the leer proper is located. The cables 56 pass under the pulleys 54 and upwardly over guide pulleys 64 and thence toward each other over winding drums 68 fixed at suitable intervals upon 110 horizontally extending winding shaft 70 carried upon the top of the framework by suitable bearings 72.

The winding shaft 70 is, by any suitable means, rotated to wind up or unwind cables 56 and thereby raise or lower the upper movable leer section. The means for this purpose herein illustrated includes a pair of chains 76 passing over suitable sprocket gears fixed on shaft 70 and operatively connected, through reduction gearing 80, to an actuating pulley 82 or sprocket wheel which 115 may be operated conveniently by hand 120

through the chain 86, or by other suitable means.

The invention includes means for insuring tightness of the relatively movable sections 5 of the leer after they have been vertically adjusted to provide for effective annealing of ware of predetermined height, and, in the present embodiment, this means not only locks the movable sections to each other in 10 fixed relation, but also acts to seal these sections together after their relative adjustment, thereby eliminating heat losses which would otherwise occur and also insuring against undesired variation of the successively predetermined lower temperatures within 15 the leer from the ware entrance end to the ware exit end.

Accordingly, in the present embodiment, an asbestos strip 90 is riveted or otherwise 20 suitably fixed to the stationary leer bottom along each side thereof and extending the full length of the leer for cooperation with the inside face of each side wall 42, as shown particularly in Figure 4.

25 Carried by the vertical members 62 of the framework along each side of the leer are a plurality of bearings 92. Within these bearings on each side of the leer is rotatably mounted a horizontal, eccentric-carrying shaft 94, extending lengthwise of the leer. Each shaft carries at spaced intervals therealong eccentrics 96, which are movable by rotation of their shafts into and out of pressing or locking engagement with vertically 30 extending metal strips 98 fixed to the movable side walls 42 of the leer. The vertically movable leer section is substantially rigid but is sufficiently flexible to permit the eccentrics 96 to cam the side walls inwardly 35 toward each other and against the asbestos strips 90, thereby to accomplish not only a locking of the vertically movable section of the leer in its adjusted position, but, at the same time, resulting in a sealing together of 40 the relatively movable sections. When a new adjustment is required for ware of different height, the shafts 94 are rotated by handles 97, or otherwise, to release inward pressure on the leer side walls, thus permitting 45 them to be raised or lowered to a new position.

As shown in Figure 5, at least some of the cams 96 are provided with flanges receiving between them the strips 98 for the purpose 50 of insuring against any longitudinal shifting of each eccentric-carrying shaft 94 with respect to the metal strips 98.

With the construction described, it is evident that a considerable range of variation 60 of the height of the leer, measured internally, is provided, there being no variation of the side wall insulation effectiveness as a result of variation of height within this range. Also, the cam action of the shafts 94 provides a lock holding the movable section in

adjusted position, at the same time sealing it to the immovable section.

What is claimed is:

1. A leer including a floor, ceiling and insulating side walls, raising and lowering mechanism for varying the distance of the ceiling from the floor, and means cooperating with the side walls for locking the ceiling in adjusted position. 70

2. A leer having a relatively fixed floor, a ceiling and insulating side walls cooperating with said floor, said ceiling and side walls being vertically movable, raising and lowering mechanism cooperating with the ceiling and side walls, and side wall engaging devices for urging said side walls toward each other into sealing relation with said floor. 75

3. A leer having a relatively fixed floor, a ceiling and insulating side walls cooperating with said floor, said ceiling and side walls being vertically movable, raising and lowering mechanism cooperating with the ceiling and side walls, sealing elements between the side walls and floor, and side wall 80 engaging devices for urging said side walls toward each other into sealing engagement with said floor. 90

4. A leer having a floor, and having a ceiling and side walls movable with respect 95 to said floor, raising and lowering mechanism for varying the position of said ceiling and side walls, with respect to said floor, and sealing elements cooperating with said side walls and floor. 100

5. A leer having a floor, and having a ceiling with side walls movable with respect to said floor, raising and lowering mechanism cooperating with the ceiling and side walls, and side-wall engaging cam devices for urging said side walls toward each other into sealing relation to said floor. 105

6. A leer having a floor, and having a ceiling with side walls movable with respect to said floor, raising and lowering mechanism cooperating with the ceiling and side walls, and side-wall engaging cam locks for urging said side walls toward each other into fixed frictional sealing engagement with said floor. 110

7. A leer having a floor and having a ceiling with side walls movable with respect to said floor, raising and lowering mechanism cooperating with the ceiling and side walls, a cam-carrying shaft for each side wall, cam locks carried by each shaft engageable with the cooperating side wall, said side walls being movable toward each other by said cams into frictional locking and sealing engagement with said floor. 120

8. A leer construction including a fixed floor, an enclosing framework, a ceiling with side walls cooperating with said floor and supported by said framework, said side walls receiving between them said floor, raising 130

and lowering mechanism carried by said framework and cooperating with said ceiling and side walls for varying the distance of said ceiling from said floor, the lower portions of said side walls being movable below said floor.

9. A leer construction including a fixed floor, an enclosing framework, a ceiling with side walls cooperating with said floor and supported by said framework, said side walls receiving between them said floor, raising and lowering mechanism carried by said framework and cooperating with said ceiling and side walls for varying the distance of said ceiling from said floor, the lower portions of said side walls being movable below said floor, and sealing devices carried by said framework and cooperating with each side wall and said floor for effecting a seal therebetween.

10. A leer construction including a fixed floor, an enclosing framework, a ceiling with side walls cooperating with said floor and supported by said framework, said side walls receiving between them said floor, raising and lowering mechanism carried by said framework and cooperating with said ceiling and side walls for varying the distance of said ceiling from said floor, the lower portions of said side walls being movable below said floor, a camming device for each side wall carried by said framework for urging each side wall toward the other and into frictional sealing relation with said floor.

11. A leer having a floor, ceiling and insulating side walls, the ceiling and floor being relatively movable, raising and lowering mechanism for varying the distance between said ceiling and said floor, and relatively movable locking devices cooperating with said side walls for effecting sealing and non-sealing of the parts.

12. A leer having a floor, ceiling and insulating side walls, said ceiling and side walls being movable with respect to said floor, and said side walls embracing the floor and having their lower portions movable below the floor level, and relatively movable locking devices cooperating with said side walls for effecting sealing and non-sealing between said side walls and said floor.

13. A leer having a ceiling, a floor and side walls embracing and receiving between them said floor, the ceiling and side walls being movable with respect to said floor, and raising and lowering mechanism for effecting relative vertical movement between the side walls and the floor while the floor is embraced by and received between the side walls.

14. A leer having a ceiling, side walls, a

floor, and heating elements, fixed tracks mounted in said leer, a ware conveyor belt slideable on said tracks, and heat resisting lubricating inserts in said tracks cooperating with said conveyor belt.

15. A leer having a ceiling, side walls, a floor and heating elements, angularly extending conveyor-supporting tracks mounted in said leer, a ware conveyor belt slideable on said tracks, and heat resisting lubricating inserts in said tracks cooperating with said conveyor belt.

16. A leer having a ceiling, side walls and a floor, heating elements above the floor surface, angularly arranged tracks above said heating elements, a ware conveyor belt slideable on said tracks, and heat resisting lubricating inserts in said tracks cooperating with said conveyor belt.

17. A leer having a ceiling, a floor and side walls, said side walls and floor being relatively movable, heating elements above the floor, tracks above said heating elements, a ware conveyor belt slideable on said tracks, said side walls embracing and receiving between them said floor, heating elements, tracks and conveyor belt, and raising and lowering mechanism for effecting relative vertical movement between the side walls and the floor while said side walls embrace and receive between them said floor, heating elements, tracks and conveyor belt.

18. A leer having a ceiling, side walls fixed thereto, and a floor, said side walls and floor being relatively movable, heating elements above the floor, tracks above said heating elements, a ware conveyor belt slideable on said tracks, said side walls embracing and receiving between them said floor, heating elements, tracks and conveyor belt, and raising and lowering mechanism supporting said ceiling and side walls for varying the distance of said ceiling above said belt, the lower portions of said side walls being movable vertically below said floor by said mechanism.

19. A leer having a ceiling, side walls fixed thereto, and a floor, said side walls and floor being relatively movable, heating elements above the floor, tracks above said heating elements, a ware conveyor belt slideable on said tracks, said side walls embracing and receiving between them said floor, heating elements, tracks and conveyor belt, raising and lowering mechanism supporting said ceiling and side walls for varying the distance of said ceiling above said belt, the lower portions of said side walls being movable vertically below said floor by said mechanism, and devices cooperating with said walls and floor for securing them together and releasing them.

LOUIS BEON.
